UNITED STATES PATENT OFFICE.

JOHN A. HEBB, OF UNIONTOWN, PENNSYLVANIA, ASSIGNOR TO THE HEBB COKE DRAWER CO., OF UNIONTOWN, PENNSYLVANIA.

COKE-DRAWING MACHINE.

SPECIFICATION forming part of Letters Patent No. 728,101, dated May 12, 1903.

Application filed August 14, 1902. Serial No. 119,618. (No model.)

To all whom it may concern:

Be it known that I, JOHN A. HEBB, a citizen of the United States, residing at Uniontown, in the county of Fayette and State of Pennsylvania, have invented certain new and useful Improvements in Coke-Drawing Machines, of which the following is a specification, reference being had therein to the accompanying drawings, forming part of this specification, in which—

Figure 1 is a plan view of my improved coke-drawing machine, showing it in position in front of an oven-door, portions of the conveying mechanism and the beam being broken away. Fig. 2 is a vertical longitudinal section on the line II II of Fig. 1. Fig. 3 is a detail view showing the beam-supporting roller. Fig. 4 is a sectional view at right angles to Fig. 2, indicated by the line IV IV of Fig. 1. Fig. 5 is a partial similar view, on an enlarged scale, showing one of the clutch mechanism in engagement.

My invention relates to apparatus for drawing coke from the oven wherein a traveling structure is provided with a reciprocating beam having a rake-head adapted to be extended into and withdrawn from the oven to empty the contents therefrom. The present application refers more particularly to the means for imparting movement to the rake-beam. Related subject-matter is embodied in separate applications bearing the serial numbers 119,617, 119,619, 119,620, 120,559, and 125,644.

Referring now to the drawings, A represents the framework of a portable carriage carrying a turn-table B, upon which are mounted the various manipulative portions of the machine.

Mounted in suitable bearings is a main shaft 4, driven at one end by a suitable prime mover, as a steam-engine. Centrally mounted in step-box 6 is a vertical shaft 7, in driving engagement with shaft 4 by bevel-gears 9 10, by which shaft 7 is continuously driven.

The beam-supporting and beam manipulating framework and mechanism are mounted on the two main standards 22 22 at each side of the central shaft 7, which standards are secured to the upper side of the turn-table and

are provided at their upper portion with pillow blocks or bearings 23, in which is mounted the cross-shaft 24, provided at its middle portion centrally, above the center of the machine, with driving-pinions 25, in driving engagement with racks 26, secured to beam 27, the central web of which extends between pinion 25 and rests upon a roller 28, journaled on shaft 24, by which the weight of the beam is carried and the teeth relieved from the strain of gravity. Above the beam is a roller 29, connected by links 30 to shaft 24, which roller provides an upper bearing for the beam and holds it in engagement with the driving-pinions. The forward end of the beam is provided with a pivotally-attached rake-head 31, adapted to fold backwardly on coming into contact with the coke on entering the oven and to be automatically extended by tension of a spring 32 at the back end of the beam and connected with the arms 35 of the fork by rod 33. On each side of the beam, freely journaled on shaft 24, are the conical friction-drums 36, provided on their inner portions with peripheral bevel-teeth 37, the teeth of both of such drums being in constant engagement with a driving bevel gear-wheel 38, secured to the upper end of the shaft 7, by which both friction-drums are constantly driven in opposite directions. The hub of each drum bears outwardly against a collar 39, secured to shaft 24, by which the teeth 37 of the drum are held in mesh with driving-wheel 38. Beyond the friction-drums at each side is a surrounding friction-sleeve 40, each of which is provided with a hub portion in driving engagement with shaft 24 by a spline or key 41, so that when either of such sleeves is brought into frictional engagement with its drum by shifting the sleeve upon the drum, it will transmit movement to shaft 24 in one direction or the other, according to which drum 36 is utilized. The shifting operation is secured through lever 42, pivoted at 43 and connected at 44 to a shifting bar 45, mounted in suitable bearings on the upright supports 22 and provided with forks 46, engaging collars or flanges on the hub of sleeve 40, as clearly shown in Figs. 1 and 4. By this construction when lever 42 is shifted in

either direction but one of the friction-clutches will be engaged, and by adjusting the sleeves 40 so that in their intermediate inoperative position they are just clear of the 5 friction-drums the necessary movement of lever 42 is reduced to a minimum. By these means upon holding one of the pair of clutches in contact the power of shaft 7 will be imparted through bevel-wheel 38, drum 36, to 10 its connected sleeve 40, and consequently to shaft 24, rotating pinions 25 in one direction, so as to carry the beam into the oven the desired distance when the clutch is released. Upon reversing the operation the opposite 15 pair of clutches are thrown into engagement, consequently reversing the rotation of pinions 25 and withdrawing the beam as far as necessary to effect the withdrawal of the coke by the rake, when the clutches are again 20 thrown out of engagement or will become automatically disengaged at any point by merely releasing pressure on the clutches. When the rake has been extended to the desired point in the oven and lowered upon the coke, 25 a rapid alternative engagement of the clutches will impart a corresponding reciprocating movement of short range to the beam, when the points of the rake will be worked down into the coke, the pivotal joint providing for 30 the longitudinal movement. The inner end of the beam is raised and lowered by operative mechanism under the control of the operator, so that the height of the rake may be varied at varying positions of the beam; but 35 such mechanism does not form *per se* any part of the present invention.

Having described my invention, what I claim is—

1. In a coke-drawing machine; mechanism 40 for transmitting longitudinal movement to the beam consisting of a driving-shaft, a driving-pinion secured to the shaft, toothed wheels loosely journaled on the shaft and provided with clutch portions, clutch devices in spline 45 engagement with the shaft, adapted to engage said portions, and means for driving the toothed wheels in opposite directions, substantially as set forth.

2. In a coke-drawing machine; mechanism 50 for transmitting longitudinal movement to the beam consisting of a driving-shaft, a driving-pinion secured to the shaft, bevel-wheels loosely journaled on the shaft and provided with clutch portions, clutch devices in spline 55 engagement with the shaft adapted to engage said portions and means for driving the toothed wheels in opposite directions, substantially as set forth.

3. In a coke-drawing machine; mechanism 60 for transmitting longitudinal movement to the beam consisting of a driving-shaft, a driving-pinion secured to the shaft, bevel-wheels loosely journaled on the shaft and provided with clutch portions, clutch devices in spline 65 engagement with the shaft adapted to engage said portions, and a driving bevel-wheel in

engagement with the bevel-wheels, substantially as set forth.

4. In a coke-drawing machine; mechanism for transmitting longitudinal movement to 70 the beam consisting of a driving-shaft, a driving-pinion secured to the shaft, bevel-wheels loosely journaled on the shaft, and provided with frictional clutch-faces, movable clutch members in spline engagement with the shaft 75 adapted to engage said faces, and a driving bevel-wheel in engagement with the bevel-wheels, substantially as set forth.

5. In a coke-drawing machine; mechanism for transmitting longitudinal movement to 80 the beam consisting of a driving-pinion secured to the shaft and adapted to engage a rack on the beam, bevel-wheels loosely journaled on the shaft and provided with tapering frictional clutch-faces, movable clutch 85 members in spline engagement with the shaft, and provided with similarly-tapered faces adapted to engage the faces of the bevel-wheel clutch members, and a driving bevel-wheel in engagement with the bevel-wheels, substantially as set forth. 90

6. In a coke-drawing machine; mechanism for transmitting longitudinal movement to the beam consisting of a driving-shaft, a driving-pinion secured to the shaft and adapted 95 to engage a rack on the beam, bevel-wheels loosely journaled on the shaft and provided with tapering frictional clutch-faces, movable clutch members, means for shifting said clutch members alternately into contact, and a driving bevel-wheel in engagement with the bevel-wheels, substantially as set forth. 100

7. In combination with a reciprocating beam provided with a longitudinal rack, a driving-shaft, a pinion secured to the shaft 105 and in engagement with the rack, bevel-wheels loosely journaled on the shaft and provided with frictional clutch-faces, movable clutch members in spline engagement with the shaft adapted to engage said faces, and a driving bevel-wheel in engagement with the bevel-wheels, substantially as set forth. 110

8. In combination with a reciprocating beam provided with a longitudinal rack; a 115 driving-shaft, a pinion secured to the shaft and in engagement with the rack, links engaging the shaft and provided with a roller adapted to bear upon the beam, bevel-wheels loosely journaled on the shaft and provided 120 with frictional clutch-faces, movable clutch members in spline engagement with the shaft adapted to engage said faces, and a driving bevel-wheel in engagement with the bevel-wheels, substantially as set forth. 125

In testimony whereof I affix my signature in presence of two witnesses.

JOHN A. HEBB.
